KEYLESS LOCK

Original Filed Nov. 14, 1924 2 Sheets-Sheet 2

Fig. 6.

UNITED STATES PATENT OFFICE.

MEADE WILDRICK, OF HONOLULU, TERRITORY OF HAWAII, ASSIGNOR TO W-H KEY-LESS LOCK COMPANY, LIMITED, OF HONOLULU, TERRITORY OF HAWAII, A CORPORATION OF THE TERRITORY OF HAWAII.

KEYLESS LOCK.

Application filed November 14, 1924, Serial No. 749,923. Renewed January 7, 1926.

To all whom it may concern:

Be it known that I, MEADE WILDRICK, a citizen of the United States of America, residing at Honolulu, Territory of Hawaii, have invented certain new and useful Improvements in Keyless Locks; and I do hereby declare the following to be a full, clear, and exact description of the invention, such as will enable others skilled in the art to 10 which it appertains to make and use the same.

This invention relates to "keyless locks" and has for one of its objects to provide a lock of this character which will be simple 15 in construction, comparatively inexpensive to manufacture and which will readily lend itself to numerous applications, such for example, as automobile locks of various characters, baggage locks, safe locks, builders' 20 hardware and in fact, any form of lock where permutation discs may be employed.

The invention relates in general to the type of lock shown in my prior Patent No. 1,373,283, granted March 29, 1921; in the 25 prior patent granted to Alexander G. Hatch, October 6, 1925, No. 1,555,969; in the prior patent granted to Meade Wildrick & Alexander G. Hatch, No. 1,565,132, December 8, 1925; in the application of Meade Wildrick, 30 entitled Wheel for keyless locks, filed October 17, 1924, Serial No. 746,178; and in the application of Meade Wildrick & Alexander G. Hatch, entitled Keyless lock, filed September 24, 1924, Serial No. 739,665.

With the above and other objects in view which will appear as the description proceeds, the invention consists in the novel details of construction and combinations and arrangements of parts more fully herein- 35 after described and particularly pointed out in the appended claims.

Referring to the accompanying drawings, forming a part of this specification, in which like reference characters designate like parts 40 in all the views.

Figure 1 is a front elevational view of a simple bolt lock employing the present invention.

Figure 2 is a vertical sectional view 45 through the lock shown in Figure 1, taken approximately on the plane indicated by the line 2-2 in said Figure.

Figure 3 is a similar view at right angles thereto taken approximately on the plane indicated by the line 3-3 of Figure 2. 55

Figure 4 is an enlarged perspective view of one of the permutation wheels constituting a feature of the present invention.

Figure 5 is an enlarged perspective view of the bolt employed in this form of lock. 60

Figure 6 is a central vertical sectional view of a padlock incorporating the present invention.

Figure 7 is a transverse sectional view 65 through the said padlock, taken approximately on the plane indicated by the line 7-7 of Figure 6.

Figure 8 is a horizontal sectional view taken approximately on the plane indicated by the line 8-8 of Fig. 6, and 70

Figure 9 is an enlarged perspective view of the bolt employed in this form of the invention.

Referring more particularly to Figures 1 to 5 inclusive, the numeral 10 indicates generally the lock casing or housing which preferably takes the form of a casting recessed as indicated at 11 to accommodate the permutation wheels as will be clear from Figures 2 and 3. A shaft 12 is mounted on the said casing 10 and extends through the recess 11 and has rotatably mounted upon it a plurality of permutation wheels 13. The front face of the casing is closed by the plate 14 secured thereto in any suitable manner, as by the screws 15, and the said plate is provided with a plurality of openings 16 through which portions of the wheels 13 may project whereby the said wheels may be manipulated in the usual well known 85 manner.

As best shown in Figures 3 and 4, the wheels 13 comprise the large discs 17, the peripheries of which bear suitable indicating characters 18 and the said discs are 90 provided with reduced axially extending hubs 19 which in turn are provided with raised annular flanges 20, spaced longitudinally from the body portion 17 and from the ends 21 of the said hubs. Inasmuch as 95 the discs are assembled in close axial alignment as shown in Figure 3, this construction provides a pair of spaced annular grooves 24 and 25 for each wheel which are adapted 100

to accommodate projections carried by the locking bolt, as will appear more fully below.

The circumference of the hub 19 which forms the bottom of the groove 25 is preferably provided with a plurality of longitudinally extending notches which are adapted to be engaged by portions of detent springs 27 whereby the wheels may be retained in any desired set positions as will be readily understood.

A locking bolt 30 is slidably mounted in the recess 31 provided in the casing and the said bolt carries a plurality of downwardly extending pins or projections 32 which are adapted to extend into the annular grooves 24 and 25 above described and as is clearly illustrated in Figures 2 and 3. The annular flanges 20 provided on the hubs 19 are each cut away as indicated at 33 to provide a passageway whereby the projections 32 may be moved from one side to the other of the flanges 20 as will be readily understood.

In order to slide the bolt 30, the latter is provided with an elongated slot 35 through which passes the transverse shaft 36, one end of which may carry a knob 37, the other end of which is provided with a collar 38 retained thereon by means of a set screw 39. Said shaft 36 has rigidly secured to it adjacent one face of the bolt 30, a collar 40 which is provided with a radial slot 41 adapted to receive a pin or projection 42 rigidly carried by the bolt 30. It thus results that when the shaft 36 is oscillated by means of the knob 37, the bolt 30 will be reciprocated longitudinally through the pin and slot connection, as will be readily understood. A coiled spring 43 may be seated in a recess 44 provided in the end of the bolt to move the latter in one direction (see Figure 3).

Coming now to the form of the invention shown in Figures 6 to 9 inclusive, wherein there is shown a padlock embodying the principles of the invention, the numeral 50 indicates the inner housing which carries the permutation wheels 13, which in this instance, are rotatably mounted on a hollow shaft or sleeve 51 mounted in the said housing. The open lower face of this housing is closed by means of a plate 52, having openings 53 through which portions of the said wheels project, whereby they may be manipulated. The said inner housing is encased in an outer casing 54 and carries the bolt 55, which bolt is provided with extensions or projections 56 for coacting with the wheels 13 in the manner above disclosed in connection with Figures 1 to 5.

At the right hand side of the lock as viewed in Figure 6, a recess 57 is provided between the inner and outer casings, which is adapted to receive the shackle member

58 having the offset portion 59, the upper edge 60 of which is adapted to contact with the surface 61, with the outer casing 54 to act as a stop for limiting the outward movement of the shackle. The shackle is indicated at 62 and is pivotally connected as at 63, to the member 58 as will be readily understood from Figure 6. The other end of the shackle is provided with a toe 64 which is received in a slot 65 provided in the bolt 55, and said toe engages a lug 66, also carried by the said bolt, to lock the shackle as will be readily understood from the drawings.

The bolt 55 is normally urged toward the left or locked position as viewed in Figure 6 by the coil spring 67 which is received in the recess 68 formed in the bolt and the offset end of the bolt is provided with a projection 69 which is adapted to be engaged by one end of a plunger member 70 which is mounted in a bore 71 formed in the outer casing or housing 54. The said plunger 70 is provided with a projection 72 which extends through the side wall of the casing 54 where it may be pressed by the thumb or finger and a coil spring 73 is co-operatively associated with the said plunger 70 to normally urge it outward to the position shown in Figure 6.

In assembling the lock, the wheels 13 are first introduced into the inner housing 50 in axial alignment, whereupon the sleeve 51 is introduced from the left of the said housing as viewed in Figure 6, through the bores of the wheels, the shackle parts are next properly positioned within the outer housing 54 whereupon the inner housing is introduced into the outer housing and the pin 75 passed through the bore of the sleeve 51 and threaded into the left hand wall of the casing 54. During this operation of course, the shackle 62 and its associated parts are maintained in the dotted line position, shown in Figure 6, so that the pin 75 may be introduced through the aperture 76, provided in the outer housing. However, when the shackle is moved to locked or full-lined position, the extension 59 of the shackle 58 will move down over the right hand end of the pin thereby preventing its accidental or intentional withdrawal.

While the annular flanges 20 of the wheel 13 in both forms of the present invention have been shown as plain, it will be obvious that if desired, they may be provided with false recesses or slots, similar to those shown in my co-pending applications Serial No. 746,178, filed October 27th, 1924 and Serial No. 747,777 filed November 4, 1924. It is also obvious that any or all of the various features described and claimed in the other co-pending applications above mentioned, may be incorporated in the present invention, without a radical change and there-

fore it is not wished to be limited to the above disclosure except as may be required by the following claims.

Having thus described my invention, what

5 I claim is:

1. In a keyless lock, the combination of a housing; a plurality of permutation wheels rotatably mounted in said housing, each of said wheels being provided with a reduced 10 axially extending hub having a raised annular flange thereon, each flange having a passageway extending through it; and a longitudinally slidable bolt mounted for movement in said housing in a plane parallel 15 to the axis of said wheels, having lateral projections adapted to move through said passageways from one side to the other of said flanges.

2. In a keyless lock, the combination of a housing; a plurality of permutation wheels rotatably mounted in said housing, each of said wheels being provided with a reduced 20 axially extending hub having a raised outwardly extending annular flange thereon, spaced from the body of said wheel and from the end of said hub, each flange having a passageway extending through it; and a longitudinally slidable bolt mounted for movement in said housing in a plane parallel 25 to the axis of said wheels, having lateral projections adapted to move through said passageways from one side to the other of said flanges.

3. A wheel for keyless locks comprising a disc having a reduced axially extending hub provided with a circumferential flange thereon, spaced from the body of said disc to provide an annular channel adapted to accommodate a portion of a locking bolt 40 when the latter is in one position, said flange being also spaced from the end of said hub and having a cut away portion providing a passageway from one side thereof to the other, the end portion of said hub, exterior 45 of said flange serving to space said flange from an adjacent wheel and to thereby provide a second annular channel adapted to accommodate said locking bolt portion when it is in another position.

50 4. In a padlock, a casing; a plurality of permutation wheels rotatably mounted in said casing, each of said wheels being provided with a reduced hub having an annular flange on the exterior thereof, each flange being cut away to provide a passageway therethrough; a bolt slidably mounted in said casing, provided with projections adapted to move through said passageways from one side to the other of said flanges; a 55 shackle slidably mounted in said casing, provided with a toe adapted to be engaged by said bolt; and means for moving said bolt.

60 5. In a padlock, a casing; a plurality of permutation wheels rotatably mounted in said casing, each of said wheels being pro-

vided with a reduced hub having an annular flange on the exterior thereof, each flange being cut away to provide a passageway therethrough; a bolt slidably mounted in said casing, provided with projections 70 adapted to move through said passageways from one side to the other of said flanges; a shackle slidably mounted in said casing, provided with a toe adapted to be engaged by said bolt; manually operable means for 75 moving said bolt in one direction and spring means for moving said bolt in the opposite direction.

6. In a padlock, an inner casing member; a plurality of permutation wheels rotatably 80 mounted in said casing member; a bolt controlled by said wheels, slidably mounted in said member; an outer casing member; a shackle slidably mounted between said casing members; and means carried by said 85 outer casing member for moving said bolt.

7. In a padlock, an inner casing member; a plurality of permutation wheels rotatably mounted in said casing member; a bolt controlled by said wheels, slidably mounted in 90 said member, an outer casing member; a shackle slidably mounted between said casing members; said shackle having a stop shoulder adapted to coact with said outer member to limit its movement; and means 95 carried by said outer casing member for moving said bolt.

8. In a padlock, an inner casing member; a sleeve carried by said member; a plurality of permutation wheels rotatably mounted on said sleeve; a bolt controlled by said 100 wheels, slidably mounted in said member; an outer casing member; a shackle slidably mounted between said casing members and coacting with said bolt; and a pin passing through said sleeve and engaging said outer casing member to lock the parts together.

9. A lock comprising a casing, a locking member mounted therein, said member being movable from an effective to an ineffective position, and vice versa, and a plurality of permutation wheels mounted in said casing with their axes of rotation in alinement and extending in a direction parallel with that of the direction of movement of said locking member, said wheels having parts accessible through slots in said casing so as to be independently settable and other parts lying in the paths of movement of parts of said locking member and preventing effective movement thereof except when set in a predetermined relation, said movement-obstructing parts comprising a plurality of lugs, extending from said locking member, and a plurality of externally disposed slotted circular abutment elements, one on each wheel, each extending into the path of movement of one of said lugs, said wheels being independently rotatable without limit when said locking mem- 115 120 125 130

ber is in either of its two positions but preventing effective movement of said member from one position to the other except when so set as to bring the slots in their abutments in registration with said lugs, thereby permitting said lugs to pass through said slots to the opposite sides of the respective abutments as the locking member is moved from either of its two positions to the other.

10. A permutation wheel for a keyless lock, said wheel comprising a "setting" por-

tion of relatively large diameter, a lateral extension of smaller diameter, and an externally disposed circular abutment member surrounding said extension, said member having effective abutting faces spaced from the ends of said extension and a radial slot extending through said abutment and forming a passageway therethrough, from the space at one side to the space at the opposite side. 15 20

MEADE WILDRICK.
